VISIBILITY THRESHOLD DEVICE FOR INDICATING CHANGES IN THE OXYGEN CONTENT OF AIR

John Curtis Hartley, Kingston, Pa.

Application December 30, 1947; Serial No. 794,747

2 Claims. (Cl. 88—14)

(Granted under the act of March 3, 1883, as amended April 30, 1928; 370 O. G. 757)

The invention described herein may be manufactured and used by or for the Government of the United States for governmental purposes without the payment to me of any royalty thereon in accordance with the provisions of the Act of March 3, 1883, as amended April 30, 1928.

My device provides a method and apparatus for promptly indicating a deficiency of oxygen in a restricted space such as a coal or metal mine, or a sewer, a manhole, or an empty petroleum products storage tank liable or suspected to contain air deficient in oxygen, by means of the reduction in the intensity of illumination produced by a flame when the oxygen content of the air is lowered. Wherever warned by my device of any dangerous composition of the air, an inspector should seek the cause and correction of the dangerous condition without the delay and expense incident to collecting a sample for a laboratory quantitative analysis.

Fluctuations in the intensity of illumination given off by a miner's lamp when transported from place to place are difficult to measure by the unaided eye. I provide an opaque shield for attachment to suspending rods of a miner's lantern, or the like, with a plurality of light filters of different degrees of light-stopping power, mounted over transverse apertures in said shield.

The shield is mounted at a fixed distance from the center of the flame of the lantern then a plurality of light filters are selected which will stop all light from the flame whenever the percentage of oxygen falls to one of a plurality of predetermined minimums. When no light is passed by any of the light filters, a dangerous condition is indicated which demands prompt correction.

When methane or other inflammable gas is present in the air within a mine, the flame of a miner's safety lamp lengthens which intensifies the heat applied to bi-metallic warning devices with which the improved miner's safety lamps are equipped so that with my attachment for warning that there is a deficiency of oxygen, an inspector can quickly detect both the presence of inflammable gas or a deficiency of oxygen.

In the accompanying drawings which illustrate a preferred form of my device:

Figure 1 is an elevation of the device.

Figure 2 is an elevation of a miner's safety lamp with my device attached thereto.

Figure 3 is a section on the line 3—3 of Figure 1.

Fig. 4 is an elevation of a modified form of the device.

In these drawings:

An opaque shield formed of two curved layers

11; 12 is provided with transverse apertures 13, 14, 15, and 16. Each aperture is closed by one of a plurality of light stopping filters 17, 18, 19, and 20; each of said filters having a different light stopping power from that of the companion filters. The shield layers 11; 12 are formed with rod clamping extensions 21; 22 on one side and a reinforcing rib 23 on the opposite side, all being held together by suitable rivets 24, or the like. It will be observed that the margin to which the rib 23 is attached is made concave.

My device is attached to a standard miner's safety lamp 25 by forcing the clamping extensions 21; 22 against one of the lamp suspending rods 26 and due to the resilience of the material, these extensions will yield to admit the rod, then by springing the flexible shield 11 to force the opposite side against an adjacent rod 26 secure the device transversely of a zone of illumination from the burner 27 of the lamp.

When so mounted on the lamp, my device remains at a constant fixed distance from the flame of the burner 27 and in its application to lamps of different types and construction, the density 20 of the filters is dependent on the intensity of illumination on the inner surface of my shield, said intensity varying as the square of the distance between the shield and the flame of the burner while the oxygen content of the air remains constant.

30 A mirror 28 may be mounted on the lamp 25 at an angle of 45 degrees to the vertical axis of the lamp by means of suitable brackets 29. The shield serves to cut off a direct view of the flame so that by looking at the filters it may be readily determined whether or not light is passing through one or more of the filters. Before entering a manhole or a storage tank which may contain air which is deficient in oxygen, a workman 35 may lower a miner's lamp equipped with my shield and cooperating mirror 28 into the tank or the like while watching the mirror for any danger indication.

It should be understood that the present disclosure is for the purpose of illustration only, and 45 that the invention includes all modifications and equivalents which fall within the scope of the appended claims.

What I claim is:

1. In a device for indicating changes in the 50 composition of air in a restricted space by means of fluctuations in the intensity of illumination produced by the flame of a miner's lamp or the like, the improvement which comprises an attachment for a miner's lamp including an opaque shield formed of two layers each having a plu-

rality of apertures, means for fastening said layers together with the apertures in one layer in alignment with those of the companion layer, said shield being formed with a curvature substantially concentric with the center of the flame of the lamp lateral extensions on each layer adapted to engage suspending rods of a miner's lamp, when the layers are clamped together, and a plurality of aperture closing light filters mounted between said layers, each of a different light-stopping power from the remaining filters.

2. In a device for indicating a deficiency of the oxygen content of air in a restricted space by means of fluctuations in the intensity of illumination produced by a flame of a portable lamp of the safety lamp type provided with substantially vertical spaced rods, the improvement which comprises a shield of two layers of opaque material provided with a plurality of aligned apertures, a light filter closing each aperture and differing in light-stopping power from each of

5 the other filters, said filters being retained between said layers of said shield, said shield layers being formed with a curvature substantially concentric with the center of the flame of the lamp when in operative position with lateral margins curved to fit suspending rods of said lamp, and means for uniting said shield layers.

JOHN CURTIS HARTLEY.
